UNITED STATES PATENT OFFICE

2,247,973

TYPOGRAPHICAL DISTRIBUTING MACHINE

Herman T. Sundstrom and Clarence A. Stopple,
Houston, Tex., assignors to Mergenthaler Linotype Company, a corporation of New York

Application July 3, 1940, Serial No. 343,696

20 Claims. (Cl. 199—16)

This invention relates to distributing mechanisms for typographical composing machines, such as "Linotype machines" of the general organization represented in Letters Patent of the United States to O. Mergenthaler No. 436,532, wherein circulating matrices are released from a magazine in the order in which their characters are to appear in print and then assembled in line, the composed line transferred to the face of a slotted mold, the mold filled with molten metal to form a slug or type-bar against the matrices which produce the type characters thereon, and the matrices thereafter returned through a distributing mechanism to the magazine from which they started.

More particularly, the present improvements are directed to that class of machines of the shiftable multiple magazine variety, wherein the magazines are movable upwardly and downwardly in the machine frame to bring a selected magazine into operative relation to the assembling and distributing devices. There are several different commercial models which make up this class of machines and the present improvements have been developed particularly in connection with those models which include as features the improvements disclosed in U. S. Letters Patent No. 2,125,681 to Richard R. Mead.

In those machines, the shifting of the magazines is effected by a crank handle located at the front of the machine and connected to a magazine elevating mechanism adapted to provide for a quick, easy and smooth shifting of the magazines in changing from one to another. The magazine elevating mechanism has been so designed that a single turn of the crank handle will effect a change from one magazine to the next, and moreover, the effort involved in shifting the magazines has been lightened to such extent that a force of one pound applied to and moved through one rotation of the crank handle will lift a load of sixty pounds covering a two and one-half inch movement of the magazines. The magazines are removably mounted on separate base frames conjointly constituting a shift frame, and the selected magazine is located in operative position by means of gage bars arranged in pairs at opposite sides of the magazines. The gage bars are supported at their lower ends upon aligning pieces on the fixed machine frame in position to present surfaces adapted for engagement with the under sides of aligning lugs projecting laterally from the opposite sides of the magazine base frames at both ends thereof. In providing for the engagement

of the gage bars with the aligning lugs, the former are arranged to slide forwardly and backwardly so as in one position to stand clear of the aligning lugs during shifting of the magazines and in the other position to stand beneath the aligning lugs on the base frame of the selected magazine.

While the foregoing magazine shifting arrangement constitutes a decided improvement in the art, the movement of the gage bars into and out of the path of the aligning lugs on the base frames of the magazines requires clearance for their free movement, and because of the "floating" character of the shift frame (as contrasted with the earlier forms wherein the magazine base frame was located and supported by banking blocks) and the ease with which the magazines can be raised and lowered, the aligning lugs may not seat firmly on the supporting surfaces of the gage bars unless strict attention is paid to that seating operation. Moreover, the gage bars are usually locked against full movement to inoperative position unless all matrices have been distributed, thus avoiding shifting of the magazines at a time when injury to the matrices or other parts of the machine might occur, or the matrices might be distributed to the wrong magazine. The gage bars are capable of a partial movement, however, to actuate feelers for determining whether or not matrices are in the course of distribution, and during such movement of the gage bars the magazine may be unseated inadvertently. In either event, whenever the magazine is unseated, its upper receiving end is out of alignment with the channel entrance and matrices being distributed therethrough frequently lodge at this point, so that any attempt to shift the magazines at such time causes damage or delay, or both. Furthermore, continued distribution of matrices when this occurs results in the matrices piling up in the channel entrance, and much time is lost while the channel entrance is being cleared and the cause of the difficulty discovered and remedied.

The present invention is directed to certain improvements in the distributing mechanism in or for a typographical machine of this character in conjunction with the magazine raising and lowering mechanism, the general idea being to provide safety devices to prevent the unlocking of the magazine shift frame except at the proper time and to interrupt temporarily the distribution of matrices at any time when the magazine in operative position is unseated. More specifically, the movement of the gage bars to inop-

erative position, that is, clear of the aligning lugs on the magazine base frame, is prevented by a feeler bar arranged between the entrance channel and the upper receiving end of the magazine to detect the presence of matrices lodged at that point, the movement of the feeler bar being in response to a slight initial movement of the gage bars toward inoperative position. In conjunction with this feeler mechanism, a locking device which renders inoperative the vertically reciprocating matrix lifting finger of the distributor box which presents the matrices individually to the distributing screws is provided to act whenever the shift frame is moved and unseats the magazine then in operative position. The locking device comprises a yielding detent which is adapted to engage the matrix lifting finger to hold it in its upper position, the rocking of the detent being controlled by trigger means acting in response to a very slight movement of the shift frame to which it is connected by a suitable train of connections. When the shift frame is moved to bring the magazine to its proper seating position, the trigger means is reset and the locking detent positively moved out of engagement with the matrix lifting finger to permit the latter to resume its normal operation.

In the accompanying drawings, the invention has been shown merely by way of example and in preferred form, but obviously many variations and modifications may be made therein and in its mode of application which will still be comprised within its spirit. It is to be understood, therefore, that the invention is not limited to any specific form or embodiment, except insofar as such limitations are specified in the appended claims.

Referring to the drawings:

Fig. 1 is a side elevation of the upper portion of a machine of the class described equipped with the present improvements;

Fig. 2 is an enlarged view of the upper portion of the structure shown in Fig. 1, some of the parts being omitted;

Fig. 3 is a rear elevation of a part of the upper portion of the machine in the region of the line 3—3 of Fig. 2, looking in the direction of the arrows, shown with the central portion omitted;

Fig. 4 is a fragmentary side elevation, partly broken away, showing the magazine shift frame locking device;

Fig. 5 is a view similar to Fig. 4, showing the parts in a different position for comparison;

Fig. 6 is a side elevation, partly in section, of the upper part of the structure shown in Fig. 1, looking from the opposite side of the machine; and

Fig. 7 is a rear elevation, partly in section, of the structure shown in Fig. 6.

The improvements disclosed in the Mead patent referred to are incorporated in one type of commercial machine along with the improvements set forth in United States Letters Patents Nos. 2,155,588 and 2,155,589, both in the names of Frank C. Frolander and Harold A. Burt. The Frolander and Burt inventions deal with the so-called "mixing" of matrices, that is, withdrawing matrices indiscriminately from two different magazines located one above the other and composing them in the same line. This type of machine, among other things, requires the provision of two distributor boxes and two sets of distributing screws for simultaneously distributing the matrices to their respective channels of the particular magazines from which they were drawn,

the upper or lower magazine as the case may be. The present improvements are shown in the accompanying drawings as embodied in the "mixing" type of machine because they were developed in connection with a machine of that character, but it will be obvious from the description to follow that they may be incorporated in any multiple magazine machine if necessary or desired.

10 In the embodiment illustrated, the machine is equipped with four magazines, A¹, A², A³ and A⁴, carried in a shift frame A⁵ arranged to be raised and lowered to bring selected pairs of magazines into operative position between the assembler mechanism B at the front and the distributor mechanism C at the rear.

Since the present machine contemplates mixing matrices from the two magazines in operative position, there are provided two distributors C¹ and C² (see Figs. 1 and 2), the upper distributor being connected through a channel entrance D with the lower magazine in operative position, and the lower distributor through a shorter channel entrance D¹ with the upper magazine in operative position. The matrices X, as usual, are fed to a distributor box C³ associated with the upper distributor (Figs. 6 and 7), wherein they are supported by their upper projecting ears x on rails c as they traverse the box. The distributor box C³ is of standard construction, being provided, as usual, with a vertically reciprocating slide or finger c¹ which acts to raise the matrices individually to a higher level. According to whether the matrices are to be returned to the lower or upper magazine in operative position, they are distinguished by well known font selecting mechanism (the details of which are fully set forth in the last mentioned Frolander and Burt patent) which allows those belonging in the upper magazine to pass to the lower distributor C² and raises those belonging in the lower magazine to the upper distributor C¹.

As already stated, the magazines A¹, A², A³ and A⁴ are removably mounted on separate base frames A⁵, conjointly constituting a shift frame which is arranged to be moved upwardly and downwardly in the machine frame. The selected magazines are located in operative position by means of gage bars F arranged in pairs at opposite sides of the magazines and connected by rigid members F¹. These gage bars F are supported at their lower ends upon aligning pieces F² (the rear aligning piece only being indicated) on the fixed machine frame and engage the aligning lugs F³ projecting laterally from the opposite sides of the magazine base frames A⁵ at both ends thereof. When the selected magazines are brought into operative position, the aligning lugs F³ of their base frames will be engaged by the gage bars F, which thus locate the magazines in proper position with respect to the assembling and distributing mechanisms. In providing for the engagement of the gage bars with the aligning lugs, the former are arranged to slide forwardly and backwardly on the fixed aligning pieces F² so as in one position to stand clear of the aligning lugs during the shifting of the magazines and, in the other position, to engage the aligning lugs on the base frames of the selected magazines, the movement of the gage bars being controlled through a pair of arms F⁴ rising from a rock shaft F⁵ and engaging at their upper ends behind pins F⁶ extending inwardly from the connecting members F¹. With this arrangement, when it is desired to change from one pair of

magazines to another, the rock shaft F^5 is rotated in the appropriate direction to draw the gage bars F forwardly against the tension of their actuating springs F^7 out of the path of the magazine aligning lugs F^3 , and then, after the magazines have been raised or lowered to the required extent, the rock shaft is rotated in the opposite direction to permit the springs F^7 (which really effect such reverse rotation of the shaft) to restore the gage bars to their original or active position in engagement with the aligning lugs on the base frames of the magazines selected.

At this time it may be convenient to explain that the rock shaft F^5 is controlled by a selecting handle J located at the front of the machine within easy reach of the operator while seated at the keyboard (see Fig. 1). When the magazines are to be shifted, the handle J is turned from its normal position to draw the lever G downwardly to rock the shaft F^5 and consequently move the gage bars forward.

With regard to the magazine raising and lowering mechanism, suffice it to say that the elevating mechanism is operated by a crank handle H also located at the front of the machine within easy reach of the operator, the turning of the crank H effecting a rotation of the shaft H^1 which in turn operates suitable gearing contained within the housing H^2 , all as set forth in the Mead patent referred to heretofore.

When the selected pair of magazines are seated in operative position, one or more of the aligning lugs F^3 (depending upon which pair of magazines are in operative position) bank against the surfaces f of the gage bars F which define the lower walls of the recesses f^1 therein. During a magazine changing operation, the magazines are raised slightly to unseat the aligning lugs F^3 so that the gage bars can be moved forwardly with ease to unlocking position clear of the aligning lugs, whereupon the magazines are free to be adjusted to bring the lugs F^3 on the base frame of the newly selected magazines into alignment with the recess f^1 . The gage bars F are then allowed to be returned to their locking position and the magazines lowered the slight distance necessary to seat the lugs F^3 on the surfaces f of the recesses in which they engage. It is only when the aligning lugs F^3 on the magazine base frames are in such seated condition that the magazines are in proper operative position to cooperate with the magazine entrance channels D and D^1 at their upper matrix receiving ends. When the aligning lugs F^3 are unseated, the bottom walls a of the magazines stand slightly above the bottom walls d of the entrance channels D and D^1 . In such event, the matrices X descending through the entrance channels D and D^1 from the distributors C^1 and C^2 , respectively, strike the raised lower walls a of the magazines and frequently lodge at that point, either bridging the gap between the entrance channels and the magazines if stopped by their lower ears x^1 or protruding from the magazine if stopped by their upper ears x .

According to the present improvements, a feeler device M , having two blades m and m^1 , is arranged so that the blades move across the upper receiving ends of the magazines in operative position in the space between the upper ends of the magazines and the lower ends of the channel entrances D and D^1 . The feeler blades m and m^1 are supported from below by two vertical links m^2 fastened to opposite ends of the

blades, the lower ends of the links m^2 being pivotally secured to levers N and N^1 mounted on a horizontal shaft O supported in the machine frame. The feeler M is adapted to be actuated by the initial movement of the gage bars F , and this is accomplished by connecting the short arm p of a bell-crank P to the gage bar connecting member F^1 by a link Q . The bell-crank P is pivoted on the shaft O and its long arm p^1 is connected near its free end to the lever N by a tension spring R which extends between a pin p^2 on the bell-crank P and a ring n formed on a lug n^1 which rises from the top edge of the lever N .

An adjusting screw N^4 , arranged in the machine frame and adapted to contact the top edge of the arm N , and an adjusting screw P^1 , at the end of the long arm p^1 of the bell-crank P arranged to contact the lower edge of the arm N , are provided for locating the bell-crank P and lever N in proper working relation to one another.

An arm N^2 of the lever N which extends forwardly on the opposite side of the shaft O has one end of a link N^3 pivoted thereto, the opposite end of the link being pivotally connected to a latch S located below the arm N^2 . One end of the latch S is pivoted as at s to the machine frame and the link N^3 is adapted to support the latch so that it lies substantially parallel with the link Q when in operative position, the free end of the latch S beyond the link N^3 being bent sidewise to engage loosely in a notch or recess q formed in the top edge of the link Q .

With the foregoing arrangement, when the handle J is actuated to move the gage bars F forward to inoperative position, the initial movement of the member F^1 through the link Q rocks the bell-crank P in a clockwise direction (Fig. 2), the bent end of the latch S riding freely in the recess q of the link Q and being raised slightly but not enough to clear the rear edge q^1 of the recess. This rocking of the bell-crank P rotates the lever N also in a clockwise direction and draws the feeler blades m and m^1 downwardly across the upper ends of the magazines sufficiently to contact any matrices which may be lodged at that point. In the event that one of the feeler blades strikes a matrix and is resisted in its downward movement, the spring R yields to limit the pressure of the feeler blade on the matrices and allow the link Q and the bell-crank P to partake of a slight additional movement. However, since the continued movement of the bell-crank is relative to the lever N , the latch S is not raised enough to clear the rear edge q^1 of the recess q in the link Q (see Fig. 5) and engages therewith to prevent further movement of the link Q and, hence, the withdrawal of the gage bars F to inoperative position. Thus, the latch S positively limits the movement of the gage bars F and consequently the rocking of the bell-crank P , thereby preventing the application of undue pressure on the feeler M which would result from excessive tensioning of the spring R . On the other hand, if there are no matrices present to be engaged by the feeler blades m and m^1 , the bell-crank P and lever N continue to move in unison and the upward movement of the arm N^2 lifts the latch S clear of the recess q (see Fig. 4) so that the gage bars F are unlocked for movement to inoperative position clear of the aligning lugs F^3 on the magazine base frames. When the magazines have been shifted, the bell-crank P is rocked counterclockwise as the gage bars F are returned to operative position by the springs F^7 . The lever N is rocked in unison with the bell-

crank P due to the engagement therewith of the screw P¹ carried by the bell-crank, and hence the feeler M is returned to its original position and the latch S reengaged in the recess q of the link Q.

As stated at the outset, it frequently happens that the magazines are not seated properly in operative position after they have been shifted, or they become unseated during an attempt to unlock the gage bars for shifting, and fail to register accurately with the channel entrances D and D¹. In the case of an actual shifting of the magazines, the failure of the magazines to seat properly is usually the result of careless or thoughtless neglect to deliberately effect the seating after the gage bars are returned to operative position. In the latter instance, however, the unseating is usually the result of accident or inadvertence. It may arise from the mere attempt to move the gage bars, the movement dislodging the aligning lugs F³ from the surfaces f¹ of the gage bars F, or from accidentally turning the crank H at the time the handle J is moved. Then too, it may occur inadvertently as a result of familiarity with the earlier magazine shifting arrangements (previously referred to briefly) wherein it was necessary to lift the magazines clear of their banking blocks in order to unlock them for shifting.

Referring to Figs. 3, 6 and 7, the safety device to interrupt the presentation of the matrices X to the distributors C¹ and C² when the magazines are unseated comprises a trigger-released locking detent T adapted to hold the matrix lifting finger c¹ against operation. The lifting finger c¹, as is well known, is carried at the end of an arm c² pivoted at c³ in the distributor box C³ and adapted to be reciprocated vertically by the rocking of a vertical arm c⁴ in response to the rotation of a cam c⁵ on the distributor C¹, all in the usual manner.

The locking detent T is pivoted at its lower end to the machine frame, as at t, and has a shoulder t² formed at its upper end adapted to engage beneath the arm c² carrying the matrix lifting finger c¹ when the arm is in its upper position. The movement of the detent T is under the control of a trigger mechanism including a cam plate U and a spring U¹ controlled by the movement of the shift frame A⁵ to which the plate U is connected by means of a lever arm U² and a link U³. The cam plate U and lever U² are formed on a housing U⁴ loosely mounted on the shaft O, the lever extending rearwardly and being pivotally connected as at u to one end of the link U³ whose opposite end is pivoted as at u¹ to the shift frame A⁵. The cam plate U is formed on its periphery with a series of three radially extending camming elements U⁵ (the number will vary according to the number of magazines or operative positions of the shift frame) which have abrupt sides and sharply rounded ends. These camming elements U⁵ are spaced apart circumferentially of the plate U to accord with the extent of movement of the shift frame from one position to another and are adapted to contact a roller Z carried by a vertical portion z of a plate Z¹ loosely mounted on the shaft O for relative vertical movement. A horizontal extension z¹ of the plate Z¹ overlies the housing U⁴ and the spring U¹ is connected to the end of the extension z¹ and a reduced portion o of the end of the shaft O. A vertically extending rod V is arranged with its lower end secured to the extension z¹ and is slidably supported by a bracket

V¹ secured to the machine frame. A camming arm V² carried at the upper end of the rod V is removably fastened thereon between a collar v and a nut v¹. The camming arm V² presents an inclined surface v² located below and in engagement with a pin t³ projecting laterally from the detent T; and a tension spring V³ is attached to the end of the camming arm V² and a second pin t⁴ on the detent T to provide a yielding connection between the detent and its actuating mechanism.

When the shift frame A⁵ is in position so that the selected magazines are properly seated, the parts are in the positions shown in Figs. 6 and 7. Thus, the roller Z rests on the tip of one of the camming elements U⁵ so that the plate Z¹ is held in its uppermost position (note the clearance at Z² Fig. 7) against the tension of the spring U¹. In this position of the plate Z¹, the rod V is in its raised position so that the engagement of the inclined surface v² of the camming plate V² with the pin t³ holds the detent T clear of the matrix lifting finger arm c². When the shift frame A⁵ is moved, perhaps only slightly but enough to move the magazines out of registry with their channel entrances D and D¹, the movement of the link U³ therewith is multiplied by the lever U² and the cam plate U rotated sufficiently to have the roller Z ride off the tip of the camming element U⁵ with which it then engages, and the spring U¹ exercises itself to move the plate Z¹ downward carrying the rod V and camming arm V² with it. This movement of the parts, through the medium of the spring V³, rocks the detent T clockwise (Fig. 6) into engagement with the matrix lifting finger arm c². If the arm c² happens to be in its upper position at the time, the shoulder t² of the detent T will simply move beneath it and hold it against further operation; otherwise the detent T will strike the arm c² and the spring V³ will yield under the pull of the stronger spring U¹ until the arm c² is raised and the tension of the spring V³ can act to draw the detent into position with its shoulder t² beneath the arm. When the arm c² is thus locked against movement, it is held in the position shown in Fig. 7 where it is unaffected by the continued rotation of the cam c⁵. Upon the movement of the shift frame to reseat the same magazines or to seat different magazines in operative position, the roller Z rides up on the same or a different camming element U⁵, as the case may be, against the pull of the spring U¹, and positively restores the detent T to its inactive position by raising the plate Z¹, the rod V and the camming arm V², the retraction of the detent T being effected by the relative movement of the inclined surface v² of the camming arm V² and the pin t³ on the detent. It will be clear from the foregoing that the locking detent T is rendered active at all times when the magazines are not properly seated. While the cam-and-spring trigger arrangement for actuating the lock is sensitive to very slight movements of the shift frame in the seating and unseating of the magazines and is intended primarily to interrupt distribution of the matrices when the magazines are unseated accidentally, nevertheless, when the magazines are shifted from one position to another the roller Z rides off one camming element U⁵ and the locking device remains operative until such time as the new magazines are properly seated in operative position and the roller Z rides up on another of the elements U⁵.

As already stated, the present improvements have been shown in connection with a machine wherein pairs of magazines are brought into operative position. Obviously, however, they can be applied equally well to machines of the multiple magazine "non-mixing" type, wherein a single magazine only occupies an operative position at any one time. Moreover, while a matrix feeler arranged between the magazine entrance channels and the upper ends of the magazines has been shown, the unlocking of the gage bars in conjunction with the interrupting of distribution may be controlled by matrix feelers commonly employed elsewhere in the machine. The channel feeler, however, is preferable because an improved form of positive lock for the gage bars which cannot be forced is made available; and the yielding connection between the feeler and its actuating device not only limits the pressure of the feeler on matrices in its path but the lock is operative to prevent the application of undue pressure on the yielding connection.

Having thus described our invention, what we claim is:

1. In a typographical distributing machine, the combination of means for feeding the matrices to the distributing mechanism, a magazine shift frame adapted to be seated in operative position, and means for incapacitating said matrix feeding means when the shift frame is unseated.

2. In a typographical distributing machine, the combination of means for feeding the matrices to the distributing mechanism, a magazine shift frame adapted to be seated in operative position, and means controlled by the unseating of the shift frame for incapacitating said matrix feeding means.

3. In a typographical distributing machine, the combination of means for presenting the matrices to the distributing mechanism, a magazine shift frame adapted to be seated in operative position, and automatic means for incapacitating said matrix feeding means when the shift frame is unseated and rendering it active again when said frame is reseated.

4. In a typographical distributing machine, the combination of means for feeding the matrices to the distributing mechanism, a lock device engageable with said matrix feeding means to hold it against operation, a magazine shift frame adapted to be seated in one or another of a plurality of operative positions in the selection of different magazines, and means actuatable by the movement of the shift frame out of and into a seated position for rendering said lock device active and inactive, respectively.

5. In a typographical distributing machine, the combination of a reciprocating lifting finger for feeding the matrices individually to the distributing mechanism, a magazine shift frame adapted to be seated in one or another of a plurality of operative positions in the selection of different magazines, and a locking detent controlled by the unseating movement of the shift frame and engageable with the lifting finger to prevent its reciprocation.

6. In a typographical distributing machine, the combination of a reciprocating lifting finger for feeding the matrices individually to the distributing mechanism, a magazine shift frame adapted to be seated in one or another of a plurality of operative positions in the selection of different magazines, a locking detent engageable with said lifting finger to prevent its reciprocation when the shift frame is unseated, and trigger means

adapted to be released in response to the unseating movement of the frame to effect the actuation of the locking detent.

7. In a typographical distributing machine, the combination of a reciprocating lifting finger for feeding the matrices individually to the distributing mechanism, a magazine shift frame adapted to be seated in one or another of a plurality of operative positions in the selection of different magazines, a locking detent engageable with said lifting finger to prevent its reciprocation when the shift frame is unseated, and a cam-and-spring trigger arrangement for actuating the locking detent in response to the unseating movement of the shift frame, the cam being adapted to hold the locking detent in inactive position when the shift frame is seated and being rotatable by the movement of the frame from its seat to allow the spring to draw the locking detent into engagement with the lifting finger.

8. In a typographical distributing machine, the combination of a vertically reciprocating lifting finger for feeding the matrices individually to the distributing mechanism, a magazine shift frame adapted to be seated in one or another of a plurality of operative positions in the selection of different magazines, a locking detent engageable with the lifting finger when the latter is in its raised position to prevent its reciprocation, a pin projecting laterally from the locking detent and overlying an inclined surface at the upper end of a vertically movable shaft, a spring connecting the locking detent to the upper end of the shaft and maintaining the engagement of said pin and inclined surface, a roller near the lower end of said shaft arranged to project laterally therefrom, a cam plate underlying said roller, a spring acting to cause said roller to track on the periphery of the cam plate, a lever arm for rotating said cam plate, and a link connecting the lever arm to the shift frame, whereby movement of the shift frame to unseat it effects a rotation of the cam plate to cause the roller to ride onto a low portion thereof and allow the vertically movable shaft to descend and permit the locking detent to be rocked yieldingly by the spring connected thereto and to the upper end of said shaft for engagement with the matrix lifting finger, and whereby the locking detent is positively cammed out of engagement with the matrix lifting finger by the relative movement of the pin on the finger and the inclined surface at the upper end of the vertically movable shaft when the shift frame is again seated and its final seating movement causes the roller at the lower end of said shaft to ride up onto a high portion of the cam plate and elevate the shaft.

9. An attachment for typographical distributing machines comprising, in combination, a locking detent adapted to be secured to the machine frame in operative relation to the distributing mechanism for engagement with the matrix lifting finger thereof, means adapted to be mounted in the machine for actuating the locking detent, means adapted to form a connection between the locking detent and its actuating means to effect the rocking of the latter into and out of engagement with the matrix lifting finger, and connections adapted to be arranged between said actuating means and the magazine shift frame to render the actuating means responsive to movements of the shift frame.

10. An attachment for typographical distributing machines comprising, in combination, a locking detent adapted to be secured to the ma-

chine frame in operative relation to the distributing mechanism for engagement with the matrix lifting finger thereof, a cam adapted to be rotatably mounted in the machine for actuating the locking detent, connections adapted to be arranged to cooperate with the cam and locking detent to rock the latter into and out of engagement with the matrix lifting finger, and connections adapted to be arranged between the cam and the magazine shift frame to effect the rotation of the cam in response to the movements of the shift frame.

11. An attachment according to claim 10, including means for establishing a yielding connection between the locking detent and cam.

12. In a typographical distributing machine, the combination of a magazine shift frame adapted to be seated in operative position, a locking device for said frame, the frame being capable of a slight movement sufficient to unseat it although the locking device remains in operative position to prevent further shifting thereof, means to detect the presence of matrices in the course of distribution to their respective magazine channels and prevent the movement of said locking device to inoperative position, and automatic means to interrupt the distribution of matrices whenever the shift frame is unseated.

13. In a typographical distributing machine, the combination of a magazine shift frame adapted to be seated in operative position, a locking device for said shift frame, the frame being capable of a slight movement sufficient to unseat it although the locking device remains in operative position to prevent further shifting thereof, means for feeding the matrices to the distributing mechanism, means to detect the presence of matrices in the course of distribution and prevent the movement of said locking device to inoperative position, and means acting in response to the unseating movement of the shift frame to render said matrix feeding means inoperative and thereby interrupt the distribution of the matrices.

14. A combination according to claim 13, wherein the means to detect matrices in the course of distribution comprises a feeler movable across the upper end of the magazine in use.

15. A combination according to claim 13, wherein the matrix feeding means includes a matrix lifting finger, and wherein the means to render the matrix feeding means inoperative comprises a locking detent movable into engagement with said matrix lifting finger.

16. In a typographical distributing machine equipped with a magazine shift frame and a channel entrance for conducting matrices in course of distribution into the magazine in use, the combination of a movable locking device for said shift frame, and a yieldable detector blade movable between the upper end of the magazine and the channel entrance to detect the presence of matrices lodged therebetween, said detector blade when resisted in its movement by any such lodged matrices being yieldable with respect to said locking device and operative by such yielding to prevent the movement of said locking device to inoperative position.

17. In a typographical distributing machine equipped with a magazine shift frame and a channel entrance for conducting matrices in

course of distribution into the magazine in use, the combination of a movable locking device for said shift frame, a matrix detector blade operable by said device and movable between the upper end of the magazine and the channel entrance to detect the presence of matrices lodged therebetween, and a yieldable connection between said detector blade and locking device to limit the pressure exerted by the blade on any such lodged matrices contacted thereby.

18. In a typographical distributing machine equipped with a magazine shift frame and a channel entrance for conducting matrices in course of distribution into the magazine in use, the combination of a movable locking device for said shift frame, a matrix detector blade operable by said device and movable between the upper end of the magazine and the channel entrance to detect the presence of matrices lodged therebetween, a yieldable connection between said detector blade and locking device to limit the pressure exerted by the blade on any such lodged matrices contacted thereby, and means rendered active by the relative yielding of the locking device and detector blade to prevent the unlocking of the magazine shift frame.

19. In a typographical distributing machine equipped with a magazine shift frame and a channel entrance for conducting matrices in course of distribution into the magazine in use, the combination of a movable locking device for said shift frame, a feeler blade movable between the upper end of the magazine and the channel entrance to detect the presence of matrices lodged therebetween, a lever actuatable by the movement of said locking device to operate the feeler blade, a latch to prevent the movement of the locking device to inoperative position when the movement of the feeler blade is resisted, and connections between the latch and said lever for operation of the former by the latter.

20. In a typographical distributing machine equipped with a magazine shift frame and a channel entrance for conducting matrices in course of distribution into the magazine in use, the combination of a movable locking device for said shift frame, means for moving the locking device, a feeler blade movable between the upper end of the magazine and the channel entrance to detect the presence of matrices lodged therebetween, a bell-crank mounted to rock on a horizontal shaft, a link connecting one arm of said bell-crank to the locking device, a lever mounted on said shaft in side by side relation to the bell-crank, a spring connecting the bell-crank to said lever, a link connecting one arm of said lever to the feeler blade, a latch pivoted at one end to the machine frame, a link connecting the opposite end of the latch to the other arm of said lever, and an open recess in which the latch is adapted to engage loosely, the recess being formed in the link connecting the bell-crank to the locking device, and the loose engagement of the latch in said recess permitting the parts to partake of lost motion before the latch becomes effective so that the initial movement of the locking device will actuate the feeler blade.
